UNITED STATES PATENT OFFICE.

FRANZ BRÄUTIGAM, OF HAMBURG, GERMANY.

IMITATION PILLAR OR COLUMN AS USED FOR DECORATIVE PURPOSES.

1,095,374.

Specification of Letters Patent.

Patented May 5, 1914.

Application filed August 15, 1913. Serial No. 784,940.

To all whom it may concern:

Be it known that I, FRANZ BRÄUTIGAM, a subject of the German Emperor, residing at Hamburg, a free city of the German Empire, have invented certain new and useful Improvements in Imitation Pillars or Columns as Used for Decorative Purposes, of which the following is a specification.

The subject matter of my invention has reference to an improvement in imitation pillars, or it may be columns, as used for decorative purposes.

The new arrangement can be used on the stage of a theater or also of a circus or the like. My invention can also be advantageously turned to account when it is desired to decorate streets and public squares temporarily upon the occasion of popular festivities or other celebrations.

20 In the accompanying drawing some constructional forms of the invention are given by way of examples.

Figure 1 shows an imitation pillar viewed from the rear. It forms one half of a round cylindrical pillar, as it is assumed that this imitation is intended for the stage of a theater of which merely the front half is visible to the spectators. Fig. 2 is a lateral view, in longitudinal section, of the same imitation pillar as shown in Fig. 1. Fig. 3 is also a lateral view, as in the case of Fig. 2, but here the mechanism contained in the interior of the imitation pillar is folded together. Fig. 4 is a ground plan of the same imitation pillar as already represented in Figs. 1, 2, and 3. Fig. 4, however, is on a larger scale than the other three figures. Figs. 5 and 6 are mechanical details of Figs. 1 to 4. Figs. 7, 8 and 9 are ground plans of different styles of imitation pillars or columns.

The imitation pillar consists of a frame or skeleton, which is covered over externally with canvas, cloth or any other suitable material. The frame is composed of a number of stays *a* placed one above the other, and the said stays may be made of metal, such as iron for instance, or of wood or of any other suitable material. At both extremities each stay *a* is firmly attached to hempen cords *b* and, furthermore, the said stays *a* are also fastened to the girths *c* hanging vertically downward. The uppermost stay *e*, of which Fig. 6 gives a cross sectional view, must be suspended from a high-

lying firmly fixed object by means of the ropes *g*, *h*, *i*. The lowermost stay *f* is firmly attached either to the floor of a theatrical stage, or to the surface of a street or elsewhere as required. If the three ropes *g*, *h*, *i* be pulled tight then the canvas, or other material covering the outer surface of the frame *a*, *b*, *c*, will also be stretched out, and an imitation pillar of an absolutely deceptive appearance of reality, when viewed from a distance, is thus obtained.

Fig. 5 shows how the stays *a* may be attached to the vertical girths *c*. To each girth *c* there are sewn loops *m* in which the stays *a* rest. To the outer side of each stay *a* a transverse girth *k* is sewn to the longitudinal girths *c*. The object of these transverse girths is to enable the external canvas or other covering *n* to be firmly sewn on.

75 The longitudinal girths *c* are, as shown in Fig. 6, fastened at their upper ends to the stay *e*. This stay *e* must be bent out of a thicker stave or bar than the other stays *a* because it has to carry the whole 80 weight of the imitation pillar and is suspended in position by means of the eyes *o*.

When changing the scenery on the stage of a theater it is of great importance that the imitation pillar should be capable of 85 being moved from one point to another in the shortest possible space of time. To enable this to be effected all that is necessary is to release the lowermost stay *f* from the floor and pull the two hempen cords *g*, *h*, *i* upward, whereupon the imitation pillar will collapse together as shown in Fig. 3. In this way the pillars, as soon as they are 90 in this condition, can be rapidly shifted by means of the usual stage mechanisms.

95 Pillars of any form desired may be imitated by means of my invention. Figs. 1 to 4 are merely intended to show one application thereof by way of example. Fig. 7 shows another example, namely the front 100 half of an octagonal pillar. Fig. 8 represents a quadrangular pillar, while Fig. 9 shows a compound pillar of the so-called clustered column type.

105 What I claim as new, and desire to secure by Letters Patent, is as follows:

1. An imitation pillar consisting of a frame covered on the outside with tightly stretched canvas, cloth or other material, the frame or framework of said imitation pillar 110

consisting of stays which are suspended from vertical ropes or girths.

2. An imitation pillar consisting of a frame covered on the outside with tightly 5 stretched canvas, cloth or other material the frame or framework of said imitation pillar, consisting of stays which are suspended from vertical ropes or girths, the said stays are adapted to be folded together

in such wise as to shift them from a horizontal to a vertical position.

In testimony whereof I affix my signature in presence of two witnesses.

FRANZ BRÄUTIGAM.
